UNITED STATES PATENT OFFICE.

AXEL W. STEEN, OF LOS ANGELES, CALIFORNIA, ASSIGNOR OF ONE-HALF TO JULIA C. FOELISING, OF LOS ANGELES, CALIFORNIA.

TAKEDOWN CAMP STOVE.

Application filed September 5, 1922. Serial No. 586,144.

To all whom it may concern:

Be it known that I, AXEL W. STEEN, a citizen of the United States, residing at Los Angeles, in the county of Los Angeles and State of California, have invented new and useful Improvements in Takedown Camp Stoves, of which the following is a specification.

My invention relates to stoves, and particularly to take down stoves adapted for such purposes as camping. My objects are, first, to provide a stove that may readily be taken apart and re-assembled without the use of bolts, screws or similar devices; and, second, to furnish a construction that when taken down will comprise only pieces that are substantially flat.

Other objects and advantages will appear hereinafter, and while I show herewith and will describe a preferred form of construction, I desire to be understood that I do not limit myself to such preferred form, but that various changes and adaptations may be made therein without departing from the spirit of my invention as hereinafter claimed.

My objects are attained by the construction illustrated in the accompanying drawing, in which—

30 Figure 1 is a perspective view of the entire device; Figure 2 is an elevation of one of the sides, of which there are two exactly alike but used as right and left; Figure 3 is an end elevation of this same part; Figure 35 4 is a plan view of the top of the stove; Figure 5 is an elevation of the edge of the last named piece; Figure 6 is an elevation of the back end piece of the stove; and Figure 7 is an elevation of the front end piece.

40 Figures 8 and 9 illustrate the folding smoke stack when unfolded and ready to ship; Figure 8 being a plan view, and Fig. 9 an elevation of the bottom end of this construction.

45 Similar numerals refer to similar parts throughout the several views.

The side pieces 1 are each provided with a bottom flange 2; with a pair of vertical slots 3 close to each of their end edges; and with a pair of horizontal slots 4 close to their top edges.

50 The top piece 5 is provided with cooking holes 6 and with a rectangular smoke stack hole 7. It also has four tenons 8, spot welded to its under surface. These

tenons are of such dimensions, and they are so located, that they are adapted to engage the horizontal slots 4 near the upper edges of side pieces 1.

Back end piece 9, and front end piece 10, are each provided with two pairs of vertically notched tenons 11, adjacent their side edges. These are spot welded to their inner surfaces and are of such dimensions, and so located, as to allow them to enter the vertical slots 3 of the side pieces. When thus positioned a downward movement of the end pieces will result in the tenon notches engaging the bottom edges of their respective slots.

70 The top, sides, and ends of the stove are assembled and locked in position in the manner just indicated. A convenient procedure is to first assemble these parts in the position shown dotted in Fig. 1. The disengaged 75 end of the front piece is then lifted, and tenons 11 are made to enter their respective slots 3. The front piece is then pushed down and this locks the parts in place. To disassemble, the procedure just described is 80 reversed.

No stove bottom ordinarily is required, and the device sets directly upon the ground with its weight supported by bearing flanges 2. The front end is preferably made 85 with a large opening 12, for the introduction of fuel, and through which the necessary draft is maintained.

90 The rectangular smoke stack is constructed of four flat strips of sheet metal, continuously hinged together, side by side, in the manner shown in Figs. 8 and 9 at 13. One of the outer strips 14 is provided with a pair of longitudinally notched tenons 15. The other outer strip 16 is provided with a pair of correspondingly longitudinal slots 17. These tenons and slots may be mutually engaged by slightly springing the parts when the several strips have been swung 95 into the rectangular boxlike form of the smoke stack as shown in Fig. 1.

100 The four strips of the stack are of substantially the same length, but outer strips 14 and intermediate strips 18 have their bottom ends turned outwardly to form supporting flanges as at 19. This leaves strips 16 and 20 extending beyond the two others at the bottom, as shown at 21.

110 Extensions 21 are adapted to enter the smoke hole 7, and to position the stack on

the stove. The weight of the stack will be supported by flanges 19. The continuous hinges 13 serve to close the joints between the strips, and thus make the stack tight and capable of maintaining the draft

Having thus fully described my invention, I claim:

1. A take down stove having its side and end plates surrounding its top plate; said 10 end plates engaging said side plates by means of vertically notched tenons, and said top plate engaging said side plates by means of plain tenons.

2. A five part take down stove having its 15 side and end plates surrounding its top plate; said end plates engaging said side plates by means of vertically notched tenons, and said top plate engaging said side plates

by means of plain tenons; said side plates having bottom supporting flanges thereon.

3. A take down stove having tenon jointed sides, ends, and top; and a multiangular sectioned smoke stack comprising longitudinally hinge jointed strips, the unhinged terminal pair of which are sprung engaged by 25 means of notched tenons.

4. A take down stove having tenon jointed sides, ends, and top, and a multiangular sectioned smoke stack comprising longitudinally hinge jointed strips, the unhinged terminal pair of which are sprung engaged by 30 means of notched tenons; said stack having outwardly turned bearing flanges at corresponding ends of an opposed pair of said strips.

AXEL W. STEEN.
